UNITED STATES PATENT OFFICE

103,886

DESIGN FOR AN ADVERTISING SIGN

Charles D. Clark, West Springfield, Mass.

Application February 13, 1937, Serial No. 67,633

Term of patent 14 years

To all whom it may concern:

Be it known that I, Charles D. Clark, a citizen of the United States, residing at West Springfield, in the county of Hampden and State of Massachusetts, have invented a new, original, and ornamental Design for an Advertising Sign, of which the following is a specification, reference being had to the accompanying drawing, forming part thereof.

Fig. 1 is a plan view of an advertising sign, showing my new design; and

Fig. 2 is a side elevational view of the design shown in Fig. 1.

I claim:

The ornamental design for an advertising sign, as shown.

CHARLES D. CLARK.
